(57) **CLAIM**

The ornamental design for adjustable and convertible audio headphones, as shown and described.

DESCRIPTION

The present application is related to co-pending U.S. utility patent application Ser. No. 13/446,321, entitled "Adjustable and Convertible Audio Headphones", having a common inventor and filed on even date.

FIG. 1 is a perspective view of an adjustable and convertible audio headphone showing my new design;

FIG. 2 is a front elevational view thereof;

FIG. 3 is a side elevational view thereof;

FIG. 4 is a rear elevational view thereof;

FIG. 5 is an opposite side elevational view thereof;

FIG. 6 is a top plan view thereof; and,

FIG. 7 is a bottom plan view thereof.

Surfaces or portions shown in the figures with dashed lines form no part of the claimed design.
